UNITED STATES PATENT OFFICE.

W. WEBSTER, OF JEFFERSON COUNTY, WASHINGTON TERRITORY.

ATTACHING AND HOUSING PROPELLERS.

Specification of Letters Patent No. 20,751, dated June 29, 1858.

To all whom it may concern:

Be it known that I, WILLIAM WEBSTER, of Jefferson county, in the Territory of Washington, have invented a new and Improved 5 Mode of Attaching and Housing the Propellers of Vessels; and I do hereby declare the following to be a correct description of the same, reference being had to the accompanying drawings, in which—

10 Figure 1 is a vertical, central, longitudinal section of the after part of a vessel with my improvements; Fig. 2 is a similar section of the forward part of such a vessel; Fig. 3 is a transverse vertical section on line x, x , 15 of Fig. 2; Fig. 4 is an interior view of the after part of the ship.

The nature of my invention consists in the new mode of hanging and housing propellers hereinafter more particularly de- 20 scribed.

The first part of the invention relates to a modification of the hull of the vessel for the purpose of preparing it for the application of my improvements. The second part 25 of my invention relates to the mode of connecting the propeller blades (where there is more than one pair) so that they can be placed at right angles to each other when at work, and in the same vertical plane when 30 housed. And the third part of my invention relates to the mode of housing the propellers by slide ports of the shape required, which inclose them and convert the vessel at once into a sailing craft with unbroken hull 35 forward and aft. These three parts are all necessary to the complete realization of the benefits of my invention, and should all be combined in vessels built with express reference to this system of construction; but 40 my invention may be adapted, with good effect, to vessels already built, without such modification of the hull as I have herein indicated.

In the drawings the same part is indicated 45 by the same letter of reference in all the figures.

A marks the exterior frame of the ship; B the forepeak; C, the run; D the after propeller blades or fins; D' the forward propeller 50 blades or fins; E the after propeller shaft; F the forward propeller shaft; G the after stern slide port; H forward stern slide port; I the forward or bow slide port; J the after trunk; J' the forward trunk; K

the pipe connecting the propeller chamber with the ship's pump well; M, M, &c. air chambers; N chains attached to slide ports for hoisting and lowering them from the deck; P, P, the trap hatches in the trunks J, J'.

1. The model of the hull which I prefer resembles that of the modern clipper ships, but is much finer, having more dead wood forward and aft as shown. The lower part of the fore peak B and run C is built solid 65 inside. The simple forms of bow and stern shown in the drawings can be built at greatly diminished cost from those of the present clipper model. I place in the ends of the ship air chambers M, M, which give 70 her buoyancy, and counterbalance the weight of her propellers, thus making her easy in a seaway, and giving her greater security against foundering when water logged.

2. Where two pair of propeller blades are 75 used at right angles to each other, (see Fig. 1.) it becomes necessary in order to house them by my plan, to bring them both into the same vertical plane. In order to effect this, I place the after pair of blades on a 80 short independent shaft L (Fig. 1.) and clutch or unclutch it as required by any convenient mode. When in use, the two shafts are clutched at right angles; but when it is desired to house the propellers, the propeller 85 shaft must be turned and held by a pawl to such a position as to bring the after propeller into a vertical plane. The short shaft is then unclutched and the after slide ports G shut down, when a quarter revolution of 90 the propeller shaft will bring the forward blades into the same vertical plane with the after ones, ready to be covered in.

3. The inclosure of the propellers I effect by means of the slide ports G, H, I which 95 descend in guides or ways on each side through trunks J, J', which run down from the deck. There is a trap hatch in the bottom of the trunks opening inward, and the slide ports G, H, I, are worked up and down 100 in the trunks in any convenient way from the deck above. When the slide ports are down, the fins D, D', are inclosed in a water tight well or chamber, from which the contained water is drawn off through a pipe K 105 and conveyed to the pump well thence to be pumped in the ordinary way. When the water is removed from the propeller cham-

ber, men can descend into it to repair unship, or replace the fins or blades at pleasure. When the ports are down, the sides of the vessel are as smooth and unbroken as those 5 of an ordinary sailing ship.

Having thus fully described my invention, what I claim therein and desire to secure by Letters Patent is—

1. The sliding ports G, H, I, (of any 10 shape required by the form of hull and propellers), and connected apparatus by which they are operated for covering and uncovering the propellers substantially as specified, in combination with the trunk J and trap 15 hatch P.
2. The pipe F, leading from the propeller

chamber to the pump well, as an for the purpose described.

3. The mode of attaching and detaching the after propeller blades as and for the 20 purpose specified, in combination with the slide ports and propeller chambers.

4. The air chambers in the bow and stern as arranged relatively to the propeller recesses or chambers, substantially as and for 25 the purpose described.

The above specification signed and witnessed this fifth day of June A. D. 1858.

WM. WEBSTER.
